DESIGN FOR A RANGE

Walter Dorwin Teague, Annandale, N. J., and
Charles Stowe Myers, New York, N. Y., assign-
ors to The Floyd-Wells Company, Royersford,
Pa., a corporation of Pennsylvania

Application September 25, 1940, Serial No. 95,356

Term of patent 3½ years

To all whom it may concern:

Be it known that we, Walter Dorwin Teague and Charles Stowe Myers, citizens of the United States, residing at Annandale, in the county of Hunterdon and State of New Jersey, and in the city, county, and State of New York, respectively, have invented a new, original, and ornamental Design for a Range, of which the following is a specification, reference being had to the accompanying drawing, forming part thereof.

The figure is a perspective view of a range, showing our new design.

The other side of the range is substantially like the side shown.

We claim:

The ornamental design for a range, substan-
tially as shown and described.

WALTER DORWIN TEAGUE.
